ATTYS.

UNITED STATES PATENT OFFICE.

JOHN ALBERTOLI, OF SAN FRANCISCO, CALIFORNIA, ASSIGNOR TO SEATTLE-ASTORIA IRON WORKS, OF SEATTLE, WASHINGTON, A CORPORATION OF WASHINGTON.

CAN-CAPPING MACHINE.

Application filed October 30, 1922. Serial No. 597,826.

This invention relates to improvements in can double seaming or sealing machines and more particularly to means which will effectively control the operation of such machines and eliminate certain objections and difficulties at present encountered in the use of said machines.

The primary object of the invention is to provide, preferably in the form of an attachment, means for automatically interrupting the operation of the machine in the event a can, through failure of the machine to operate properly, does not have the cap seamed or sealed thereon. In double seamers it frequently happens that the means for moving the covers or caps into position to be seamed or sealed upon the can, fails to operate with the result that the can, having the usual filling, advances from the seamer without a cap and in such manner that the contents of the can is spilled. This produces an undesirable condition in and around the machine. In some instances, the cans which have not been sealed are advanced to the cooker. In such cases the successful continuous operation of canning machinery is interfered with and the attending objections are costly and time consuming. With my invention, the operation of the machine is automatically stopped should, for any reason, the can fail to have the cover or cap applied thereto at the proper point. An audible signal is given coincident with such operation so as to notify the attendant of the failure of the machine to operate properly.

Another object of the invention is to provide an automatic stopping and safety device of the character described which is simple as to construction, inexpensive, reliable in operation and capable of being readily and easily attached to various makes of can capping or seaming machines.

The invention possesses other advantages and features some of which, with the foregoing will be set forth at length in the following description where I shall outline in full that form of the invention which I have selected for illustration in the drawings accompanying and forming a part of the present specification. In said drawings I have shown one form of the construction of my invention, but it is to be understood that I do not limit myself to such form since the

invention as expressed in the claims may be embodied in a plurality of forms.

Referring to the drawings:

Fig. 1 represents a fragmentary side elevation of a can double sealer showing the device of my invention applied thereto.

60

Fig. 2 represents an enlarged fragmentary side elevation of the device of my invention shown in connection with certain parts of the seaming machine and illustrating the manner in which the caps control the operation of the invention.

65

Fig. 3 is a fragmentary top plan view of a part of the device of my invention, the tripping and operating mechanism thereof.

70

Fig. 4 is a fragmentary end view of the sealing machine showing in end elevation the device of my invention.

75

Fig. 5 is a fragmentary top plan view of a part of the mechanism of my invention showing the manner of its connection and operation of the control lever of a double seaming machine.

80

Fig. 6 is an enlarged fragmentary side elevation of a part of the mechanism of my invention which is automatically operated by movement of the cover or cap which latter is shown in dotted lines.

85

In carrying out the invention, one form of which is shown in detail in the accompanying drawings, in which drawings I have illustrated portions of a well-known type of double seaming machine, I provide an operating trip mechanism which is actuated by the cans and the caps therefor, as said caps or covers and cans are advanced into position to be seamed. This mechanism is associated with the means for stopping the operation of the machine so that should a cap or cover fail to be moved into position to be joined or seamed to the can, the mechanism of the invention will automatically stop the operation of the machine.

90

One way in which I carry out this is to provide a spring means normally tending to move the operating lever of the canning machine so as to stop the machine, which spring means is normally held against operation by trigger mechanism. The trigger mechanism is operated by the trip mechanism, which latter is actuated by the cans and caps. The trip mechanism includes a trip member which is engaged by the can and moved or rocked on its mounting.

100

105

When the machine is operating properly, the trip member moves freely without operating the trigger mechanism. Should the machine fail to operate properly, that is, should a cap or cover fail to be moved into position to be applied to a can during the continuous operation of the seaming machine, by a clutch arrangement associated with the trip member, said trip member will be engaged 10 by the can and moved so as to operate the mechanism which releases the trigger whereupon the spring means moves the control lever and stops the machine. Thus, it will be seen, that the continuous operation of the machine depends upon the proper advancement or movement of the caps or covers and cans into position to be sealed.

In the drawings, 1 designates the can feed mechanism of a can double seaming machine, which mechanism 1 advances the cans onto a revolving table generally designated 2, during the movement of the cans by the member 1. Mechanism generally designated 3 separates one of the caps or covers 4, from a stack thereof and causes the said covers or caps to be moved onto a table or platform 5 and to be brought into position to be applied to the cans. This mechanism automatically causes the cans and caps to be brought into proper position as is well known in the art, and it is thought need not be described in detail. In some instances the mechanism 3 fails to move a cap or cover into proper position to be applied to the can and it is when this occurs that the device of my invention operates automatically to stop the machine.

The can capping machine is controlled by an operating lever 6 pivoted intermediate 40 of its ends as at 7 to the machine. The device of my invention is connected with this lever and operated by movement of the can and the cap as will be later described.

Taking up first the description of the part of the mechanism of the invention which is associated with the lever 6, I prefer to attach a retractile spring 9 to one end of the lever 6, the other end of said spring being attached to some suitable part of the frame work of the machine, whereby said spring tends to move the lever so as to stop the machine. To hold the lever in position to permit the machine to operate, I provide trigger mechanism generally designated 10, which mechanism comprises a plurality of straight links 11, 12 and 13. The link 11 is rigidly fastened to the lever 6, and at one end is pivoted to the link 12, which latter is pivoted to one end of the link 13. The link 13 is pivoted as at 14 to a bracket or some other suitable element provided on the frame of the machine. When the links of the trigger 10 are in alinement, the lever 6 will be held against the action of the spring 9 in position to permit the machine to operate.

When the trigger is moved so that the links are inclined upwardly towards one end, as shown in dotted lines in Fig. 4, or in other words, when the links are moved out of alinement, the spring will quickly operate 70 to move the lever 6 so that the operation of the machine will be stopped.

To indicate to the operator that the machine has been brought to a stop, an audible signal, preferably a small clapper type bell 75 16, is jingled when the lever is moved into shutting off position. A brake element 17 is attached to the lever and operates when the lever is moved to shut off the machine to brake against a pulley or revolving member 18 so as to bring the machine to an immediate stop.

To operate the trigger 10, I employ a rod 19 vertically adjustably mounted in a bracket 20 attached to the frame work of 85 the canning machine. This rod is slotted intermediate of its ends as at 21 and loosely receives in its slot a crank arm 22 which is fastened to a rotary shaft 23 suitably journaled on the frame of the canning mechanism. The upper end of the rod 19 normally bears against the trigger where the links 12 and 13 are joined, so that when the rod is pushed upwardly the trigger will be released and permit the spring 9 to operate 95 on the lever 6. The shaft 23 has a pinion 24 keyed thereon, which pinion meshes with a similar pinion 25 carried on the upper end of an upright shaft 26. The shaft 26 is journaled in a suitable frame-supported bracket 100 27 and at its lower end carries a collar 28. A can trip member 29 is loosely mounted on the shaft 26 and extends at right angles thereto, said trip being supported by resting upon the collar 28. This trip, shaft 26 and associated parts are normally held in proper position, through the agency of springs 30 associated with the collar 28, and trip 29. The trip 29 is normally disposed so as to be engaged by cans A, see Fig. 2.

A clutch sleeve 31 is vertically adjustable upon the shaft 26 and has a notch 32 in its lower end, which notch is adapted to receive a projection 33 extending upwardly from the trip 29. When the clutch is in engagement, the shaft 26 is rotated when the trip member 29 is moved. Upon such rotation of the shaft, the shaft 23 will be rotated through the gears 25 and 24. Rotation of the shaft 23 will rock the crank arm 22 and lift the rod 19 upwardly and thereby release the trigger 10.

Cover or cap operated mechanism is provided for normally holding the clutch 31 disengaged and permit of free movement of the trip 29, said means operating to permit the clutch to engage only when the cover or cap fails to be properly presented for sealing, thereby preventing continuous operation of the machine to present a can which is

not sealed. This means comprises a trip member 36 which is mounted on a shaft 37 journaled in bearings 38 on an extension of the bracket 27. The member 36 is disposed 5 in the path of advancing caps shown at B in Fig. 2. As the caps are advanced they engage the trip 36 and lift the trip upwardly causing the shaft 37 to turn. An arm 40 is fixed to the shaft 37 and engages under 10 an annular flange 41 on the upper end of the clutch sleeve 31. Thus, when the shaft 37 is turned, the lever 40 lifts the sleeve 31 upwardly disengaging the projection 33 from the notch 32, permitting the trip 29 to 15 be turned freely on the shaft 26 each time that the can is advanced past the trip. Should a cap fail to be advanced in proper relation to a can, the trip 36 will not be operated and the clutch 31 will operate to 20 cause the shaft 26 to be turned when the trip 29 is engaged by the can. This as above described, operates the trigger mechanism, releasing the trigger, causing the machine to be stopped.

25 The cap operated trip is disposed so as to be engaged by a cap before the can trip is engaged. Thus, it will be seen that it is necessary that the can engage the trip 29 in order to operate the mechanism of my invention. Inasmuch as the cap and can are advanced in alinement with one another to be sealed, and the cap operates the trip 36 before the can engages the trip 29, the operation of the safety mechanism of my invention will be certain and reliable.

I claim:

1. The combination with a can capping machine having means for advancing caps and cans to be sealed in said machine, of means for stopping and starting the machine, spring means associated with said stopping and starting means and normally tending to operate said means so as to stop the machine, trigger mechanism normally holding said stopping and starting means in position to maintain the machine in operation, which trigger means operates against the action of said spring means and means for releasing the trigger means and permitting the spring means to operate, which last named means operates automatically upon failure of the machine to move a cap into position to be applied to a can.
2. The combination with a can capping machine having means for moving cans and caps preliminary to sealing caps upon the cans, of a stopping and starting lever controlling the operation of the machine, means tending to move said lever into stopping position, trigger means normally holding said lever in operating position, a can trip

member engaged and moved by cans during their advancement in the machine, means subject to operation by movement of the can trip member for releasing the trigger mechanism, a cap trip member to be engaged and moved by caps during advancement thereof in the machine, clutch means for operatively connecting the can trip with the trigger releasing means, which clutch means permits free movement of the can trip relative to the releasing means when a cap engages and moves the cap trip.

3. The combination with a can capping machine having means for advancing in proper relation caps and cans on which latter the caps are to be sealed, of a control lever, means at all times tending to operate the control lever so as to stop the machine, trigger mechanism normally holding said lever in position to maintain the machine in operation and means for releasing the trigger mechanism in the event of the failure of the capping machine to cause a cap to be moved into position to be sealed onto a can.

4. The combination with a can capping machine having means for advancing in proper relation caps and cans on which latter the caps are to be sealed, of a control lever, means at all times tending to operate the control lever so as to stop the machine, trigger mechanism normally holding said lever in position to maintain the machine in operation and means for releasing the trigger mechanism in the event of the failure of the capping machine to cause a cap to be moved into position to be sealed onto a can, which means includes can and cap operated control members arranged to be engaged and moved by caps and cans advancing in the machine.

5. The combination with a can capping machine having means for moving cans and caps in proper relation into position in the machine wherein the sealing or capping action is to take place, of a trip member which is engaged and moved by cans being advanced in the machine, of another trip member which is engaged and moved by caps advancing in the machine, which trip member is in advance of the first named trip, means adapted to be operated by movement of the first named trip for stopping the operation of the machine and means which when the cap trip is engaged and moved by a cap will permit the can trip to move independent of the stopping means and which when a cap fails to move and engage the cap trip will cause the stopping means to be operated upon movement of the can trip.

JOHN ALBERTOLI.
